ENGINE

Andre J. Meyer, Lexington, Ky., and Edward A. Hulbert, Ferndale, Mich., assignors, by mesne assignments, to Continental Aviation and Engineering Corporation, a corporation of Virginia

Application April 25, 1938, Serial No. 204,234

5 Claims. (Cl. 123—81)

This invention relates to engines and more particularly to engines of the sleeve valve type embodying preferably a single sleeve valve of the combined movement type and driven by means of a sleeve driving crank.

In many instances it is found very difficult to assemble a sleeve valve in an engine, particularly in an engine of the radial cylinder type, especially in that type of an assembly in which the sleeve valve is removed outwardly through the crankcase opening.

An object of the present invention is to facilitate the assembly of a sleeve valve with the engine and to minimize maintenance costs in time and labor by providing a novel and simplified arrangement for quickly assembling a sleeve valve in driving connection with the sleeve valve driving means. More particularly, this is accomplished by simplifying the construction of the sleeve driving means whereby to facilitate the connecting and disconnecting of the sleeve valve with the sleeve drive crank and by providing an arrangement which makes possible the ready removal or assembly of said sleeve valve through the crankcase opening.

In the drawings:

Fig. 1 is a vertical sectional view through an engine cylinder illustrating the present invention,

Fig. 2 is a fragmentary vertical sectional view illustrative of the sleeve and driving connections relative to the crankcase but showing the cylinder removed,

Fig. 3 is a fragmentary elevational view partly in section of the sleeve valve and means connecting same with the sleeve drive crank and taken on the line 3—3 of Fig. 2,

Fig. 4 is a horizontal sectional view taken on the line 4—4 of Fig. 3, but showing the sleeve valve shifted relative to the piston,

Fig. 5 is an elevational view of the sleeve after same has been laterally shifted as shown in Fig. 4 and also shifted in a direction substantially normal to the aforesaid shift illustrated in Fig. 4, whereby to clear the sleeve drive crank.

Fig. 6 is a vertical sectional view thereof taken substantially on the line 6—6 of Fig. 5,

Fig. 7 is a bottom plan view taken substantially on the line 1—1 of Fig. 6, and illustrating the notched construction of the ball socket carried by the sleeve valve and showing how the sleeve drive crank will clear the sleeve valve,

Fig. 8 is a sectional view taken substantially at right angles to Fig. 6 and showing in dotted lines the successive positions assumed by the

sleeve valve in being removed after being rotated when released from the sleeve drive crank,

Fig. 9 is an enlarged elevational view of the lower or inner end of the sleeve valve, and shows the notched construction of the sleeve drive ball socket, and

Fig. 10 is an enlarged detailed sectional view thereof taken substantially on the line 10—10 of Fig. 9.

The engine herein illustrated comprises a 10 crankcase 10 having an opening 11 and which supports the conventional crankshaft 12 connected by the conventional connecting rod 13 to a piston 14 by means of a piston pin 15. A cylinder structure 16 is bolted or otherwise secured 15 to the crankcase and includes a cylinder head structure 17. Said cylinder structure is preferably piloted in the crankcase opening 11 and is preferably bolted to said crankcase by long bolts 18 which serve to clamp the cylinder head and cylinder structure to said crankcase, as more particularly described and claimed in the co-pending application, Serial No. 203,448, filed April 21, 1938, for Engines.

The cylinder structure is ported for intake and exhaust, which ports are controlled preferably by ported sleeve valve means. The present invention is primarily concerned with the means for assembling this sleeve valve means in operative driving connection with the engine, and therefore, this invention is embodied in a sleeve valve engine having a ported single sleeve valve 20 of the combined movement type, which sleeve valve is driven by the sleeve drive crank 21 through the ball and socket connection 22. Preferably, 35 the ball and socket is carried by the sleeve valve and the ball 23 assembled with the socket 24 is provided with a hole 25 into which the crank 21 is slidably engaged. Normal sleeve valve operation is such as to always retain the sleeve drive 40 crank in engagement with the ball 23, and the present invention teaches a method of assembly and/or removal of the sleeve valve from the crankcase and embodies an improved construction which makes this possible and practical. It 45 will be noted that the socket 24 and the sleeve lug 26 are notched as at 27 to permit the end of the sleeve drive crank to skip by after being disengaged from the opening or hole 25 in ball 23.

The sleeve valve is moved in such a manner 50 as to bring the notch 27 in line with the crank 21 and thereby disengaged by merely lifting out the sleeve valve. In order, however, to manipulate the sleeve valve, the cylinder tie down bolts 55 18 are first released and the cylinder removed 55

from the crankcase as shown in Fig. 2. The process of removing the sleeve valve is herein described in detail and obviously the assembly will be substantially the reverse of the removing process.

After the removal of the cylinder, the sleeve drive crank is rotated into the position shown in Figs. 2 and 3, the crank 21 being thus positioned as far to one side as possible, the crank arm 28 lying in a horizontal position relative to the vertical cylinder axis. The sleeve and piston are then shifted laterally a distance permitted by the clearance between the connecting rod 13 and the piston bosses 29 (see Fig. 4). This partially 15 withdraws the sleeve ball 23 off of the crank 21 as clearly shown in Fig. 4. The next operation is to shift the sleeve and piston assembly in a direction at right angles to the wrist pin axis to the limit as permitted by the opening 11. This 20 last shifting causes the sleeve to rotate about its axis a little further, thus withdrawing the ball socket off the pin 21 (see Fig. 7). The notch 27 is lined up with the corner of the pin 21 and it is now possible to move the sleeve away from 25 driving connection with the sleeve drive pin 21.

However, the sleeve cannot be lifted straight out of the crankcase opening 11 because the diameter of this opening 11 is not sufficient to permit the sleeve lug to clear the sides of the 30 opening. The final removal of the sleeve is therefore obtained by rotating the sleeve valve 28, after it is clear of the sleeve drive pin 21 until the axis of the sleeve lug is positioned substantially at right angles to the axes of the wrist pin 15 and engine crankshaft 12. The engine crankshaft is preferably rotated to bring the piston substantially adjacent the top of its stroke. The sleeve and piston can now be rocked about the wrist pin 15 (see Fig. 8) as the sleeve is withdrawn through 35 the opening 11, said assembly being rocked sufficiently to permit the sleeve lug to clear the edge of the opening 11. It will be noted that the dotted line and dot and dash showings of Fig. 8 clearly illustrate this step.

It will be observed that the various steps in the 40 method above described are readily carried out in sequence and the whole removal of the sleeve valve is substantially one continuous motion. The sleeve valve can also be assembled by reversing 45 the steps in the process above described. The small notch in the ball socket and sleeve lug removes only a very inappreciable amount of ball bearing surface.

The construction and method described above 50 is illustrative of a preferred embodiment of the invention, but it will be apparent that modifications may be embodied in subsequent designs without departing from the spirit of the invention or from the scope of the appended claims.

We claim:

1. In an internal combustion engine of the sleeve valve type including a cylinder, a crankcase, a crankshaft having a crank, a sleeve valve operable in said cylinder, a piston operable in said sleeve valve, means connecting said piston with the crankshaft crank and including a piston pin and connecting rod, sleeve drive mechanism drivingly connected with said crankshaft and including a sleeve drive crank extending parallel to the said piston pin, said crankcase having an opening of a diameter greater than that of said sleeve valve and through which said sleeve valve extends, said cylinder detachably secured to said crankcase, said sleeve valve, piston and connections being constructed and arranged to

disengage the sleeve valve from said sleeve drive crank and remove same from said crankcase by laterally shifting said sleeve valve from a position for normal engine operation and rotating same through an angle limited by the throw of the sleeve drive crank, then further rotating the sleeve valve when disengaged from the sleeve drive crank to position said sleeve valve with the axis of the sleeve drive crank connecting boss substantially normal to the piston pin axis, whereby to permit the rocking of the sleeve valve about said piston pin in withdrawing the sleeve valve from the crankcase.

2. In an internal combustion engine of the sleeve valve type including a cylinder, a crankcase, a crankshaft having a crank, a sleeve valve operable in said cylinder, a piston operable in said sleeve valve, means connecting said piston with the crankshaft crank and including a piston pin and connecting rod, sleeve drive mechanism drivingly connected with said crankshaft and including a sleeve drive crank extending parallel to the said piston pin, said crankcase having an opening of a diameter greater than that of said sleeve valve and through which said sleeve valve extends, said cylinder detachably secured to said crankcase, said sleeve valve, piston and connections being constructed and arranged to disengage the sleeve valve from said sleeve drive crank and remove same from said crankcase by laterally shifting said sleeve valve from a position for normal engine operation and rotating same through an angle limited by the throw of the sleeve drive crank, then further rotating the sleeve valve when disengaged from the sleeve drive crank to position said sleeve valve with the axis of the sleeve drive crank socket substantially normal to the piston pin axis, whereby to permit the rocking of the sleeve valve about said piston pin in withdrawing the sleeve valve from the crankcase.

3. In an internal combustion engine of the sleeve valve type including a cylinder, a crankcase, a crankshaft having a crank, a sleeve valve operable in said cylinder, a piston operable in said sleeve valve means connecting said piston with the crankshaft crank and including a piston pin and connecting rod, sleeve drive mechanism drivingly connected with said crankshaft and including a sleeve drive crank extending parallel to the said piston pin, said crankcase having an opening of a diameter greater than that of said sleeve valve and through which said sleeve valve extends, said cylinder detachably secured to said crankcase, said sleeve valve piston and connections being constructed and arranged so that same can be relatively shifted from a position for normal engine operation after removal of the cylinder from said opening whereby to disengage said sleeve valve from said sleeve drive crank, said sleeve having a ball socket and ball operatively engaged by said sleeve drive pin, said socket having a portion thereof cut away to provide clearance permitting the end of said sleeve drive crank to clear said socket on disconnecting said sleeve valve from said sleeve drive pin.

4. In an internal combustion engine of the sleeve valve type including a cylinder, a crankcase, a crankshaft having a crank, a sleeve valve operable in said cylinder, a piston operable in said sleeve valve means connecting said piston with the crankshaft crank and including a piston pin and connecting rod, sleeve drive mechanism drivingly connected with said crankshaft and including a sleeve lug carried by the sleeve and

a sleeve drive crank extending parallel to the said piston pin, said crankcase having an opening of a diameter greater than that of said sleeve valve and through which said sleeve valve extends but less than the overall diameter of the sleeve valve and driving lug, said cylinder detachably secured to said crankcase, said sleeve valve piston and connections being constructed and arranged so that same can be relatively shifted from a position for normal engine operation after removal of the cylinder from said opening whereby to disengage said sleeve valve from said sleeve drive crank, said sleeve having a ball socket and ball operatively engaged by said sleeve drive pin, said socket having a V-shaped notch on the underneath portion thereof serving to provide clearance for said sleeve drive crank on removal of said sleeve valve.

5. In an internal combustion engine of the sleeve valve type including a cylinder, a crankcase, a crankshaft having a crank, a sleeve valve operable in said cylinder and provided with a sleeve crank socket, a piston operable in said sleeve valve, means connecting said piston with the crankshaft crank and including a piston pin

and connecting rod, sleeve drive mechanism driv-
ingly connecting same with said crankshaft and
including a sleeve drive crank extending parallel
to said piston pin, said crankcase having an open-
ing of a diameter greater than that of said sleeve 5
valve but less than the sleeve diameter through
said crank socket, said sleeve valve extending
through said crankcase, said sleeve valve, piston
and connections being constructed and arranged
to disengage the sleeve valve from said sleeve 10
drive crank and remove same from said crank-
case by laterally shifting said sleeve valve from
a position for normal engine operation and ro-
tating same through an angle limited by the
throw of the sleeve drive crank, then further ro-
tating the sleeve valve when disengaged from the 15
sleeve drive crank to position said sleeve valve
with the axis of the sleeve drive crank socket sub-
stantially normal to the piston pin axis, whereby
to permit the rocking of the sleeve valve about 20
said piston pin in withdrawing the sleeve valve
from the crankcase.
